UNITED STATES PATENT OFFICE

THADDEUS R. CHURCHILL, OF SIOUX CITY, IOWA

BRUSH

Application filed June 27, 1931. Serial No. 547,195.

My invention relates to bowl cleaning brushes of the type provided with a conical skirt of bristles flaring toward the handle end of the brush and encircling the handle.

This type of brush is particularly useful in cleaning water closet bowls and the skirt is employed for cleaning between overhanging flanges of such a bowl.

The efficiency of this skirt depends largely upon the flare which it possesses. The present invention deals with the problem of securing a wider flare in this type of brush than has hitherto been possible and has for its object to provide a novel construction whereby a wider flare may be secured.

Another object of the invention is to provide a more durable brush. Hitherto the flare has been produced by winding the skirt bristles upon the reduced end of the handle stick and allowing the shoulder formed between the handle and said reduced end to bear against the inner sides of the bristles to produce the flare. The bearing afforded by the sharp shoulder allows the bristles to slip circumferentially of the stick to some extent, and the present invention aims to provide a construction wherein there can be no circumferential slip of the bristles.

With these and other objects in view, my invention consists in the construction, arrangement and combination of the various parts of my device, whereby the objects contemplated are attained as hereinafter more fully set forth, pointed out in my claims, and illustrated in the accompanying drawings, in which:

Figure 1 is a side view of the head of a brush constructed according to my invention, and

Figure 2 is an axial, sectional view through the brush.

I provide the usual wooden handle 10 which has a reduced end or tip 11, for the purpose only of allowing the tip bristles to be brought together to a closed point.

The tip bristles are indicated by the reference character 12, and are bent back upon themselves to provide the second layer of bristles 13.

In constructing the brush, the usual procedure of inserting the stick into a rotatable vise is followed, the binding wire 14 being secured as at 15 to the tip 11 of the stick. The tip bristles 12 are then laid beneath the wire 14 in a usual manner, the second layer 13 projecting rearwardly around the handle while the first binding 16 is wrapped.

The second layer 13 is then laid back upon the tip layer 12 in the position shown in Figure 2, and secured by the second binding 17. The dotted lines indicate how the wire is carried from the first to the second binding.

As the second binding is wrapped, the second layer 13 will gradually push the tip bristles 12 together to provide a closed point.

The intermediate bristles are then laid on, providing a third layer 18 which is wrapped by the binding 19, the rearwardly protruding portions of the bristles being thence laid back upon themselves to form the fourth layer 20 which is thence wrapped with the binding 21 and secured.

The intermediate bristles are of sufficient length so that the binding 19 may be positioned at a substantial distance rearwardly of the binding 21, thereby producing in the bristles themselves, a shoulder 22 which serves to create the flare in the skirt bristles.

By laying on the winding 19 first, the intermediate bristles are securely held, and the winding 21, positioned forwardly of the winding 19, pulls in the bristles forwardly of the winding 19 so that the diameter of the brush at this stage of construction and at the region of the winding 21 is considerably less than the diameter of the shoulder 22.

The bulging of the shoulder 22 arises naturally from the resiliency of the bristles tending to assume as nearly a circular shape as possible in the region where they are bent.

back upon themselves. The winding 19 also aids in producing the bulge, and reinforces the shoulder from within so that it will not break down.

5 The skirt bristles are thence laid on and secured by the winding 23 which is positioned intermediate the windings 21 and 19 or forwardly of the shoulder 22.

The winding 23 is drawn tightly around the skirt bristles, pulling the intermediate regions thereof inwardly, and causing the skirt portions 24 thereof to flare sharply outwardly against the shoulder 22. The forward extremities of the skirt bristles 24 form the fifth layer 25 of the forward portion of the brush.

The skirt bristles 24 are of bassine material, while the tip bristles 12 and intermediate layer 18 are of the more pliable palmetto material. Thus the head of the brush is encased with a layer 25 of the stiffer and more wear resisting bristles, and the skirt 24 is constructed of the heavier bristles which are required for this purpose, while those layers which must be bent back upon themselves are constructed of the more pliable bristles which can be so worked.

Inasmuch as the shoulder 22 is formed of bristles instead of the smooth surface of the handle, the skirt bristles 24 will be located against the corrugation-like surface of the shoulder and will be tightly held against any possible twisting or circumferential movement. In other words, the bristles will be held against twisting movement not only by the wrapping 23 but also by frictional engagement with the shoulder 22.

The most important advantage of the invention however, resides in the greater flare which it is possible to secure in the skirt 24. In that type of brush wherein the flare is produced in the shoulder formed in the stick itself, it is possible for the skirt to close considerably toward the handle, whereas in a brush constructed according to my invention, the skirt will stand out rigidly at a greater angle to the handle than has hitherto been attained.

50 It is possible that a greater angle could be secured in the shoulder type construction by employing a handle of larger diameter than is at present used in this type of brush. However, this would involve considerably 55 more expense and would make the brush rather unwieldy.

Another advantage residing in the present brush is the much greater frictional engagement between the skirt bristles and the collared portion of the brush. It may be noted that the skirt bristles are in constant contact with the bristles of the intermediate layer from the winding 21 to the highest portion of the shoulder 22.

65 This feature combined with the rough sur-

face of the shoulder 22, provides a much more sturdy and durable construction.

Another advantage of the invention resides in the fact that as far as producing the flare is concerned, it is unnecessary to employ a handle with a reduced tip. The flare is produced independently of the tip and the latter has no bearing on the flare.

A further advantage of the invention resides in the fact that it is easier to construct this brush than the prior form of brush. It seems that the skirt bristles may be more easily held in engagement with the intermediate bristles than against the smooth, slippery surface of the shouldered tip, and the trimming of the skirt may be done on an ordinary rotary cutter trimming machine where the wider flare of my invention is secured, whereas, formerly, it was always necessary to trim the skirt by hand.

Some changes may be made in the construction and arrangement of the parts of my invention without departing from the real spirit and purpose of my invention, and it is my intention to cover by my claims any modified forms of structure or use of mechanical equivalents which may be reasonably included within their scope.

I claim as my invention:

1. In a brush, a handle stick, a set of bristles bent back upon themselves to provide two layers of bristles joined by an annular protruding collar portion formed by the bends in said bristles, a binding wrapped around said bristles between the layers thereof within said collar, a binding encircling both layers between said collar and the head end of the stick, an outer layer of bristles encircling said previously mentioned bristles, and a binding encircling said outer layer just between said collar and the head end of the stick, and drawing the intermediate regions of said outer bristles into the hollow between the collar and the head end of the stick, said outer layer projecting rearwardly and being held in flared position by said collar to form a skirt.

2. In a brush, a handle stick, a set of tip bristles secured thereto, a set of intermediate bristles secured thereto and encircling the tip bristles, said intermediate bristles being bent back upon themselves to form an annularly protruding collar, an outer layer of bristles, a winding securing said outer layer against the intermediate layer just forwardly of said collar, said outer layer projecting rearwardly and being flared outwardly by said collar to form a skirt.

3. In a brush, a handle stick, a layer of bristles secured thereto and bent upon itself to form an annularly protruding collar, an outer layer of bristles and a binding securing said outer layer upon the under layer, just forwardly of said collar, said outer layer of bristles projecting rearwardly and being 130

flared outwardly by said collar to form a skirt.

4. In a brush, a handle stick, tip bristles secured thereto, an intermediate layer of bristles bent back upon themselves to form an annularly protruding collar, a binding encircling the inner layer only of said intermediate bristles and reinforcing said collar from within, a binding encircling both of said layers forwardly of the collar, an outer layer of bristles, and a binding securing said outer layer against said intermediate bristles just forwardly of the collar, the outer layer extending rearwardly and being flared outwardly by said collar to form a skirt.

15 Signed this 1st day of June, 1931, at Sioux City, Iowa.

THADDEUS R. CHURCHILL.
